RAIL ATTACHMENT MEANS FOR USE IN RAILWAY TRACKS

Adalbert Doll, Minden, Westphalia, Germany, assignor to Vossloh-Werke G.m.b.H., Werder, Germany

Filed Feb. 25, 1958, Ser. No. 717,496

10 Claims. (Cl. 238—349)

This invention concerns the attachment of rails to railway track sleepers of any kind, such as wooden sleepers, concrete sleepers, or iron sleepers.

It has already been proposed to insert the rail flange between abutments which serve to define the track, and which can either be connected to the sleeper or are constructed as ribs of a base plate, for example, which in turn is secured to the sleeper. At the same time the rail flange usually rests on an elastic or yieldable shim such as a plate of poplar wood or rubber.

It is also known to secure the rail, which in the manner described has been mounted on a base plate, by resilient tension means which rest on top of the rail flange, depressing said flange. Conventional tension means of this kind usually consist of a spring stirrup, for example, bent from flat steel and one end of which engages in a center recess on the side of an abutment member, e.g. the rib of a base plate, remote from the rail, whereas the other end of the stirrup, which is bent over the rib towards the rail flange, presses resiliently from above on to the rail flange. The fitting of such spring stirrups on the track is very complicated, however. A special clamping screw passing through the stirrup into the rib of the base plate is also necessary in order to secure the stirrup in position.

It is an object of the invention to simplify and speed up the fitting and also the exchanging of spring stirrups, and to secure the seat thereof without the use of special means.

Another object of the invention is simultaneously to provide the possibility of using self-tensioning stirrup means which have a spring characteristic, particularly a long spring movement, favourable for the present purpose.

According to the present invention, self-tensioning spring stirrups manufactured in known manner from spring wire or rod material engage at their two shank ends in two separate recesses formed in each abutment member such as a butt strap or rib serving to define the track, and at least one recess comprises a slot open at one end of the abutment member and into which the appropriate shank end can be introduced from the side by spreading or opening out the said stirrup.

Where the abutment members are ribs, said ribs may comprise the ribs of a conventional base plate which is secured in known manner to the sleeper. Alternatively, butt straps separated from one another may be arranged on both sides of the rail flange and mounted separately on the sleeper.

The spring stirrups used for the attachment of the rail are preferably constructed so that they each have a center portion adapted to extend approximately parallel to the rail, are each bent towards the rail flange, and each merge by way of curved portions leading away from the rail into shank ends directed towards the rail and which engage in the butt strap or rib.

The invention will be described further, by way of

2

example with reference to the accompanying drawings, in which:

Fig. 1 is an elevation of a rail attachment and a base plate, the rail being shown in cross-section,

Fig. 2 is an end elevation of the attachment shown in Fig. 1, with a wooden sleeper shown in cross section,

Fig. 3 is a plan view of the rail attachment shown in Figs. 1 and 2,

Fig. 4 is a side elevation, partly in section of a wooden sleeper with a rail mounted thereon and located between two spaced butt straps,

Fig. 5 is a plan view corresponding to Fig. 4,

Fig. 6 is an end elevation of the rail attachment according to Figs. 4 and 5,

Figs. 7, 8 and 9 are elevations corresponding respectively to Figs. 4, 5 and 6, of an embodiment of rail attachment suitable for concrete sleepers, and

Fig. 10 is a modification of the construction shown in Fig. 4.

In the embodiment shown in Figs. 1 to 3, a base plate 3 is secured by means of sleeper screws 7 and interposed spring washers 8 to a sleeper 4. The base plate 3 is provided in known manner with two substantially parallel ribs 6 which extend in the direction of the rail 1, receive the flange 2 of the rail between them and define the track. Arranged between the rail flange and the base plate 3 is a resilient or yieldable shim 5.

The rail is secured to the base plate 3 and sleeper 4 by means of spring stirrups which are bent from hard steel spring bar or wire of round cross-section. The center portion 9 of each spring stirrup is intended to be parallel to the rail and is downwardly bent towards the rail flange. At its ends, this center portion 9 merges by way of arched or curved portions 10 and 11 directed away from the rail into two shank ends 12 and 13.

Each rib 6 is formed near one end with a transverse bore 14 and near its other end with a slot 15, which is open at the end of the rib. The bore 14 and the slot 15 are closed on the side of the ribs facing the rail flange.

Fig. 2 shows the operation of inserting or removing a spring stirrup. The stirrup is inserted first by one end 13 into the bore 14, in the position 9a shown in dot and dash lines, and is then brought through the intermediate position 9b, wherein its shank end is spread or opened out, into the position shown in full lines, in which it is attached to the base plate 3 with the necessary degree of security. In this position, the ribs form a lateral abutment for the center part 9 of the spring stirrup which is in contact with the rail flange.

One advantage of this construction consists in the feature that, apart from the known base plate, only one part, namely, the spring stirrup, is necessary and is easy to manufacture, mount and remove. Existing base plates can be adapted to use in the invention without difficulty. It is only necessary to form two recesses in each rib in which the ends of the stirrups can engage.

The pressure which the stirrup exerts on the rail flange is dependent upon the thickness of the stirrup, and may typically be some 1200—1600 kg. with a spring movement of 9 to 10 mm. By lengthening the spring bar or wire between the two shank ends, by forming lateral bulges in the shape of the stirrup, for example, the movement of the spring can be increased.

When the rail is secured by two spring stirrups, it is possible to raise the rail only with a force of about 1850—1950 kg. However, since the load on the sleeper is only about 100 kg. and is in any case only increased by vibration impacts to 500 kg. when driven over, the rail attachment is perfectly secure. In the embodiment shown in Figs. 4—6 the railway line 1 rests by its flange 2 directly on the surface of the wooden sleeper 4, except

for the interposition of an elastic shim 5. In this embodiment there is no base plate, but two separate butt straps 16 and 17 serving to define the track are mounted on the sleeper on both sides of the rail flange 2. Each butt strap is provided with a side flange 18 serving as a support and which, in the example shown, is on the side remote from the rail only, and is located in a suitable recess 19 formed in the surface of the sleeper. To connect the butt straps 16 and 17 to the wooden sleeper 4, two spikes 20 are driven into bores 21 in the sleeper. The spikes 20 may be rigidly connected to the butt straps 16 and 17.

Each butt strap 16 and 17, at one end region thereof is formed with a blind, transverse bore 14 and, near its opposite end, which is preferably intended to face in the direction of travel, with a slot 15 open at the end face of the butt strap but closed on the side of the butt strap facing the rail flange. The spring stirrup, formed from hard steel spring bar or wire of round cross-section, is constructed similarly as in the embodiment of Figs. 1-3. The center portion 9 is arranged to extend approximately parallel to the rail and to lie against the rail flange, and the curved portions 10 and 11 leading away from the rail merge into the two shank ends 12 and 13, which are in turn directed towards the rail. The insertion of these spring stirrups into the recesses 14 and 15 of the butt straps 16 and 17 is carried out in the same manner as described in respect of the embodiment shown in Figs. 1-3.

In the embodiment shown in Figs. 7-9 the rail 1 rests by its flange 2 on the upper surface of a concrete sleeper 24, an elastic shim 5 being interposed between the sleeper and the flange. Pairs of spikes 25 rigidly mounted on each of two butt straps 16 and 17 engage in bores 26 of sleeper dowels 27. In known manner, the two spikes 25 of each butt strap 16 and 17 and the corresponding bores 26 of the dowel are separate from one another, but so closely adjacent that a sleeper dowel 27 with dimensions conventional for concrete sleepers can be used.

The butt straps 16 and 17 with their flanges 18 and the spring stirrups 9, 10 and 11 are constructed in the same manner and arranged as in the previously described embodiments. In this embodiment of the invention the butt straps, instead of being secured to the concrete sleepers by means of spikes and dowels, may alternatively be formed with dependent portions such as bars or plates enabling said butt straps to be concreted directly into the sleepers.

Fig. 10 corresponds substantially to Fig. 6, but in this case the butt strap 16 is provided with a vertical bore 28 and is attached to a wooden sleeper 4 by means of an ordinary sleeper screw 29. A further difference consists in the feature that in Fig. 10 the steel bar or wire forming the spring stirrup 30 is longer and therefore the stirrup has a different shape. Its curved portions 31 and 32 leading from the center portion to the shank ends of the stirrup project further to both sides, resulting in a longer spring movement.

I claim:

1. For use in securing rails to sleepers in railroad track, rail attachment means comprising a pair of elongated abutment members, means to secure said abutment members fixedly relative to the sleepers in mutually spaced relationship to define the track and receive a rail flange between them, each abutment member being formed at one end region thereof with a recess substantially in the shape of a bore and at the other end region with a recess comprising a slot open in the end face of said other end region, said recesses extending from the side of the abutment member remote from the rail towards the latter, and a pair of stirrups formed of spring rod material and adapted to engage the rail flange on either side of the rail, each stirrup comprising a center portion so as to extend substantially lengthwise of said

5 rail, a curved and arched end portion at each end of said center portion, said end portions being directed away from said center portion, and shank ends continued from said end portions, respectively, said shank ends being bent back towards said center portion and being adapted to engage in said recesses, respectively, said shank ends of each stirrup being springingly spreadable lengthwise of said rail, and each stirrup being resiliently bendable between said center portion and said shank ends in a plane substantially at right angles to said rail, said center portion of each stirrup bearing with spring pressure on the adjacent flange of said rail when the one shank end is inserted in the one recess from the side of the abutment member remote from the rail and the other 15 shank end is inserted into said other recess from said end face of said abutment member through said slot by first urging said other shank end downward and spreading and then releasing it in relation to the first mentioned shank end.

2. Rail attachment as in claim 1, said one recess of each abutment member being engageable by the one shank end of a stirrup from the side remote from said rail, whereas said other recess being engageable by said other shank end of said stirrup from the slotted end of said 25 abutment member.

3. Rail attachment as in claim 1, said shank ends of each stirrup being straightlined, substantially parallel to each other and substantially in planes at right angles to the direction in which said center portion extends.

4. Rail attachment means as set forth in claim 1, wherein each abutment member with its flank adjacent said rail further constitutes a lateral abutment for the center portion of the associated spring stirrup on the side of the center portion on which its end portions are located, 35 said arched end portions of the stirrup extending beyond the ends of said abutment member.

5. Rail attachment means as set forth in claim 1, wherein the recesses in the abutment members are closed at the sides of said abutment members intended to face 40 the rail and open on the opposite sides.

6. Rail attachment means as set forth in claim 1, wherein the abutment members comprise spaced ribs on a base plate adapted to be secured on a sleeper, said ribs being provided with said recesses and having each a flank constituting an abutment surface for said rail flange and said center portion of the associated stirrup, said flank being shorter than the spacing of said end portions of said stirrup from each other.

7. For use in securing rails to sleepers in railroad 50 track, rail attachment means comprising a pair of separate, elongated butt straps, said butt straps being adapted for mounting in spaced relation on a sleeper to define the track and receive a rail flange between them, and including means to secure them to said sleeper, each butt strap being formed at one end region thereof with a blind recess and at the other end region with a recess comprising a slot open in the end face of said other end region, and a pair of stirrups formed of spring rod material and adapted to engage the rail flange on either 55 side of the rail, each stirrup comprising a centre portion so as to extend substantially lengthwise of said rail, a curved and arched end portion at each end of said center portion, said end portions being directed away from said center portion, and shank ends continued from said end portions, respectively, said shank ends of each stirrup being bent back towards said center portion and being adapted to engage in said recesses, respectively, of one of said butt straps, said shank ends of each stirrup being springingly spreadable lengthwise of said rail, and each stirrup being resiliently bendable between said center portion and said shank ends in a plane substantially at right angles to said rail, said center portion of each stirrup bearing with spring pressure on the adjacent flange of said rail when the associated butt strap is secured to said sleeper and when the one shank end is inserted 60 to said sleeper.

in the one recess from the side of said butt strap remote from said rail and the other shank end is inserted into said other recess from said end face of said butt strap through said slot by first urging said other shank end downward and spreading and then releasing it in relation to the first mentioned shank end. 5

8. Rail attachment means as set forth in claim 7, wherein each butt strap includes a lateral foot extension by which said strap is adapted to rest on a sleeper.

9. Rail attachment means as set forth in claim 8, 10 wherein the lateral foot extension on each butt strap is provided only on that side of said butt strap which is adapted to face away from the rail.

10. Rail attachment means as set forth in claim 8, wherein said lateral foot extensions of said butt straps are 15 received in shallow recesses therefor formed in the tops of the sleepers.
